UNITED STATES PATENT OFFICE

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed November 21, 1922. Serial No. 602,379.

To all whom it may concern:

Be it known that I, ADOLPH DIETSCHÉ, Junior, a citizen of the United States, and a resident of New York, borough of Queens, in 5 the county of Queens and State of New York, have invented certain new and useful Improvements in Display Devices, of which the following is a specification.

This invention relates to display devices, 10 and particularly to such devices of the class specified as are formed of sheet material and adapted for erection in display position. The object of my improvements is to provide a display device of simple construction 15 and pleasing appearance, and which may be laid flat for packing and shipping, and erected in display position by simple means.

With these ends in view my improvements comprise features illustrated in their 20 preferred embodiment in the drawing accompanying this specification, wherein:—

Figure 1 is a perspective view of the device in erected condition. Fig. 2 is a plan view of the device spread out in one plane. 25 Fig. 3 is a perspective view of a modified form of my improvements. The scale of Figs. 1 and 2 is the same. The scale of Fig. 3 is less than that of the other figures.

My improved device is preferably made 30 of cardboard and preferably of one piece thereof, although it will be obvious that it may be formed equally well of several pieces hinged together along the several dotted lines of Fig. 2. The display portion 35 preferably comprises an upright mid-panel or mid-portion 2 and opposite side portions or panels 3, 4 articulated thereto, preferably along parallel vertical lines 5, 6. These three upright panels may be of any fanciful 40 contour such for instance as the draped shield shown. Said side panels 3, 4 preferably extend below and under the bottom of said middle panel and, when the device is laid flat in one plane, may meet, as at 7.

45 Articulated at 8, 9 to the lower edges of said side panels are base members 10, 11, respectively, and said base members may also meet if desired along line 7^a extending downwardly as a prolongation of line 7, Fig. 2.

50 When said side panels are angularly disposed to each other the lower portions thereof extend rearwardly beyond their points of articulation with the mid-panel, whereby said mid-panel overhangs the base members. It will thus be seen that the de-

vice may be economically formed from one sheet of material by a suitable cut or incision of T shape and suitable scoring. For locking the device in erect position, base members 10, 11 are provided with coacting 60 locking means, herein illustrated as semi-circular ears 12, 13, cut from said base members, respectively.

The operation of erecting the device will be obvious from the drawing. Suffice it to 65 state that base members 10, 11 are folded forwardly along lines 8, 9, respectively, and then panels 3, 4 are folded slightly toward each other, thereby permitting base members 10, 11 to overlap, when ears 12, 13 may 70 be interlocked as shown in Fig. 2, thereby securely holding the device in erected position.

In the modification of Fig. 3, the lines of articulation 5, 6 are indefinite and the three 75 upright portions 2, 3 and 4 lie in a general transverse curve rather than in abruptly divided planes. Also the base members 10, 11 have the overlapping portions of Fig. 1 omitted, whereby said base members abut. 80 They may be held in abutting relation by some convenient means, such for instance as gummed strip 14.

I claim:

1. An integral display device of sheet material including in combination a display panel, the opposite lower side portions of said display panel having inreaching extensions horizontally severed from said panel at its mid-portion and vertically severed 85 from one another, and base members horizontally articulated to said opposite lower side portions respectively, the inner ends of said opposite lower side portions being adapted to extend rearwardly of said panel 90 mid-portion and said panel mid-portion being adapted to be suspended over said base members when the device is in erected position.

2. An integral display device of sheet material including in combination an upright display-panel, the opposite side portions of said display panel being vertically articulated to its mid-portion, the lower portions of said opposite side portions respectively 100 having inreaching extensions horizontally severed from said panel mid-portion and vertically severed from one another, and base members horizontally articulated to the lower edges respectively of said oppo- 105 110

site side portions, the severed portions of said opposite side portions being adapted to extend rearwardly of said panel mid-portion and said panel mid-portion being adapted to be suspended over said base members when the device is in erected position.

3. An integral display device of sheet material including in combination an upright display member, said display member having a T shaped incision in the lower mid-portion thereof whereby the opposite lower side portions of said display member have inreaching extensions horizontally detached from said display member at its mid-portion

and vertically detached from one another, 15 and base members horizontally articulated to said opposite lower side portions respectively, the inner ends of said opposite lower side portions being adapted to extend rearwardly of said display member mid-portion and said display member mid-portion being adapted to be suspended over said base members when the device is in erected position.

In witness whereof, I hereby affix my signature this 17th day of November, 1922. 25

ADOLPH DIETSCHE, JR.
